CLAIM

The ornamental design for a massage roller cane, as shown and described.

DESCRIPTION

FIG. 1 is a top left perspective view of a massage roller cane.

FIG. 2 is a left-side of a massage roller cane.

FIG. 3 is a right-side view of a massage roller cane.

FIG. 4 is a front view of a massage roller cane.

FIG. 5 is a back view of a massage roller cane.

FIG. 6 is a top view of a massage roller cane; and,

FIG. 7 is a bottom view of a massage roller cane.

The broken lines are included for the purpose of environmental structure and form no part of the claimed design.

1 Claim, 7 Drawing Sheets
